CURTAIN OR PANEL AND HANGER
STRUCTURE THEREFOR

Charles G. Cunningham, Chicago, Ill.

Application December 13, 1944, Serial No. 567,966

17 Claims. (Cl. 160—40)

1

This invention relates to improvements in adjustable devices adapted to act as screens to prevent escape of dusts or of sprayed or splashing liquids, from a space or room or alcove in which the dusts or liquids are to be confined. The invention also provides a hanger structure for curtains or drapes or screens.

The invention additionally provides a new kind of curtain or screen or panel adapted for use for lessening industrial accidents resulting from flying particles, or dust, or splashing or sprayed liquids. The stiff screens of this invention are so mounted as to be easily moved to various protecting positions and are made of tough, strong, acid-resistant plastic or nonmetallic materials, and can have any desired color or ornamentation.

A plastic which I believe particularly well adapted for making the screens or curtains herein is a new thermoplastic material known under the trade name "Saran." This material can be molded by injection, compression or extrusion methods. It is relatively cheap, is hard and tough and has a softening point of about 350°. This substance is resistant to most inorganic chemicals and to organic solvents generally. At room temperatures it is very inert to all common acids and to alkalis, with the exception of strong ammonium hydroxide. It is completely resistant to water or long immersion and completely resistant to moisture vapor transmission. It is noninflammable, resists heat, warping and distortion at relatively high temperatures. Other plastics that can be used are Bakelite, Lucite, Plexiglass, Beetle, Saran Plaskon, Tenita, Crystalite, Vinylite and Koroseal.

The invention is particularly valuable for use as a shower bath curtain in lieu of the woven fabric or Cellophane curtains now in use, and the invention provides means whereby a single or a plurality of curtains or screens may be attached to any support or to the ordinary shower curtain pole or rod to be adjusted in various directions. My invention does away with the use of rings or hooks or rollers. Each curtain is provided with marginal means by which a sealing relation between it and another curtain or between it and a tub, or the floor, or the wall or walls, can be obtained.

Objects of the invention are; to provide an entirely new curtain or screen; to provide a new shower curtain structure; to provide an entirely new mounting for curtains or screens; to provide a type of curtain which has advantages not found in the present woven fabric curtains; to provide a curtain which will not fade or mildew, which

2

is not so light and flimsy that it can be blown about by drafts to stick to the body of a bather, or to permit water to spray or pass outwardly; to provide a curtain made of separable sections, which can be sold in knock-down form, and be assembled by the user; to provide a curtain which is sanitary and long-lived; to provide a curtain made of plastic moldable material and which can be colored to match the bath room decoration; to provide a semirigid yet somewhat pliable curtain mounted to be adjusted with less effort than is required for curtains made of woven material; to make the curtain or panel of stainless and non-corrosive material, and to make it of oil cloth or linoleum or other waterproof substance which can be easily and readily cleaned and sterilized; to provide an arrangement of a curtain or of curtains by which it or they can be easily positioned; which can be easily adjusted for convenience in cleaning a bath tub and the shower chamber or which can be easily and quickly arranged to confine the spray while adjusting the water valves for temperature; to provide a novel form of hanger which can be used for hanging curtains at windows or doors and which is adjustable to raise or lower the curtain or drape, and for moving the curtain or drape nearer to or farther from the window, door or wall; to provide a type of panel-formed unit, the elements of which are adapted to be held in operative relation by means which interlocks the margins of a plurality of the panels or sections; to provide flexible and resilient sealing means for inter-curtain engagement and for engagement with the walls, tub or floors; to provide a type of curtain to which water will not cling to create unsanitary condition or cause odors due to dampness; to provide a structure which is easy to assemble and easy to hang; to provide means by which curtain- or panel-supporting elements can be attached either to an ordinary shower curtain or other rod, or to two vertically placed rods which extend from tub to ceiling or from floor to ceiling; to provide a new extensible rod structure which can be frictionally or pressure-held between the tub and ceiling or the floor and the ceiling; and to provide a unit knock-down structure for supporting and adjusting curtains and drapes of any kind.

Features of the invention include all details of construction shown, along with the broader ideas of means inherent in the disclosure. Features, objects and advantages of the invention will be set forth in a description of said drawings, and in said drawings—

55 Fig. 1 is a front elevation showing my inven-

tion in relation to a bath tub alcove and bath tub, with the parts in sealing position;

Fig. 2 is a plan taken at the level of line 2-2 of Fig. 1;

Fig. 3 is a plan view taken approximately at the level of line 3-3 of Fig. 1, with the hangers of the tracks omitted, and with the tops of the panels shown in elevation;

Fig. 4 is a vertical detail section taken approximately on line 4-4 of Fig. 3 to show the relation of the vertical and horizontal sealing elements respectively to the wall and to the top surface of the tub;

Fig. 5 is an enlarged fragmentary plan view of one of the panels shown in Fig. 3 showing the relation of the sealing element to the wall;

Fig. 6 is a fragmentary detail perspective of one of the flexible and resilient sealing elements;

Fig. 7 is a front elevation partly in section showing the hanger construction and means for attaching and adjusting it;

Fig. 8 is a section on line 8-8 of Fig. 7, with one of the curtains connected with one of the hanger slides;

Fig. 9 is a vertical cross-section showing the hanger brackets at one extreme of adjustment;

Fig. 10 is a view illustrating the relation of a curtain to a hanger and of the hanger to the tracks;

Fig. 11 is a detail outer face view of one of the sections of which the curtain or panel is formed;

Fig. 12 is a top plan view of Fig. 11;

Fig. 13 is a view looking at the right end of Fig. 11;

Fig. 14 is a detail section at the top of the panel, taken on line 14-14 of Fig. 11;

Fig. 15 is a section at the bottom of the panel taken on line 15-15 of Fig. 11;

Fig. 16 is a detail section taken on line 16-16 of Fig. 11 showing the section through an ornamentation and stiffening bead;

Fig. 17 illustrates how my invention may be applied to two upright rods instead of to a single horizontal rod, and illustrates a novel form of, adjustable upright rod;

Fig. 18 is a plan section on line 18-18 of Fig. 17 with the covering casing omitted;

Figs. 19, 20 and 21 illustrate the action of the sealing members when the curtains are slid past one another to finally assume, for example, the approximate positions of Figs. 1 and 3.

The following description is illustrative of my invention, as applied to a bath alcove and as attached to the ordinary shower-curtain rod or bar, or to a pair of vertical bars.

Referring first to Fig. 1. The numeral 1 generally indicates a shower bath alcove having a tub 2 therein. The shower nozzle is shown in Figs. 2 and 3 and is indicated by the numeral 3 and the usual water valve operating elements are indicated at 4.

Referring to Figs. 7, 8 and 9. The usual shower curtain rod is indicated at 10. On this rod are attached two track-supporting and adjusting devices, generally indicated 11 and of identical construction so that the parts are interchangeable. Each device 11 receives one end of the track, which track therefore bridges the devices. Each structure 11 includes a circular disk 14 having a second circular and flanged disk 15 rotatable therein on a center eccentric to the center of the disk 14. This second disk has an opening 16 which receives the shower curtain rod 10, and this opening is eccentric to the center of the disk 15 and this disk 15 is divided into

two parts along a line 17 which passes through the opening 16. The parts of this disk 15 are flanged at both ends as at 19 (see Fig. 7) to prevent axial movement of its parts in the disk 14.

5 A third or hanger or track-carrying disk 20 is rotatable in an opening 30 of disk 14 and has an opening 21 which in this instance is rectangular and which receives the end portions of a series of tracks 22 (in this instance four) spaced 10 apart by spacer elements 24 to provide ways 23, in each of which slides a hanger 25. There are three of these hangers 25. Through a diametrically placed opening in the third disk 20 and through openings in these tracks and spacer elements passes a pin 29 which releasably secures the parts against detachment. Movement of the pin is prevented by the wall of the opening 30 of the disk 14, in which opening the third disk 20 rotates freely. This is shown in 15 Fig. 8. The disk 20 has a flange 31, only at the inner side, to prevent axial motion.

The first disk 14 is formed in two parts which are hinged together as at 32 and there is means generally indicated at 33 for forcing the parts together to cause the parts of the second disk 15 to clamp the rod 10 as shown in Figs. 8 and 9. This clamping means in this instance includes a wing nut threaded on an eye bolt, pivoted to the upper section of the disk 14, the bolt being received as shown, in slots 35 of the upper and lower sections of the disk 14. The disk 15 is provided with a handle 36 which extends inwardly as shown in Figs. 7 and 9 by which to rotate it to raise and lower the disk 16, or hold the disk 15 stationary while the disk 14 is adjusted about the disk 15. After adjustment the parts may be clamped as shown. Comparison of Figs. 8 and 9 shows that there is a relatively large range of adjustment. The disk 14 or the disk 15 may be adjusted in either direction from the position shown in Fig. 8, but during adjustment the hangers 25 remain in vertical position, because of the rotatability of disk 20 in disk 14.

A very large number of separate angularly adjusted positions for disks 14 and 15 may be had in relation to the vertical and in relation to each other. In Fig. 9 both disks have been swung through an angle of 90° from their normal positions in Figs. 8 and 17. In Fig. 9 dot-and-dash line positions of disks 14 and 20 have been indicated to show how disk 14 can be adjusted about disk 15 after disk 15 has been adjusted to a 90° position. In Fig. 17 dot-and-dash line positions of the disks 14 and 20 have been indicated to show how the disk 14 can be adjusted about disk 15 while the latter remains in its normal position. Disk 14 can be vertically adjusted by swinging disk 15 by means of its handle 36 and after the disk or disks have been adjusted, the whole assembly may be clamped to the rod or bar. It is noted that this device provides means not only for adjusting vertically for causing the bottom of the curtain to have some desired relation to a surface, but can also adjust inwardly and outwardly from an upright surface to space the curtain at some predetermined distance in relation to a surface or to a window or to a door.

Finishing covers (see Figs. 7 and 8) are provided for the disks 14 and rod 10. The cylindrical casings 38 fit over the disks 14 and extend to the wall. A casing 39 fits over the casings 38 as shown. Thus, the casing structure is continuous from wall to wall. The casing or cover 39 is open at the lower side as at 40 to allow for movement and clearance of the hangers. The casings

or covers 38 are open as at 41, to clear braces 42 and to allow the casings 38 to be "clipped" over the devices 11. Thus, neither casing 38 or 39 is a complete cylinder.

By reference to Fig. 7 it will be noted that the bead 50 of each hanger extends some distance beyond the upper part of the hanger, to allow the sealing elements, later described in detail, to engage the wall before the upper part of the hanger abuts the inner surface of one of the disks 14.

A pair of braces 42 are provided, which are suitably clamped as at 43 to the rod 10 and which are secured at their outer ends to the wall, to keep the rod from rotating in its wall supports under the weight of the assembly when the hanger disks are adjusted, for example, as in Fig. 9. Under these conditions there is considerable leverage applied tending to rotate the bar 10. The plastic material of which the curtains are made is very light in weight so that leverage is not excessive. However, when curtains of greater weight are to be hung the elements 42 may be needed.

The hanger structure, including the tracks 22, hangers 25, spacers 24 and pin 29, is believed to be new per se as a structure for slidably mounting curtains, which is very cheap to manufacture and very efficient. The tracks are made of bronze and the hangers of steel. Referring to Figs. 9 and 8, it will be seen that each hanger 25 slides between two rails 22. The top of each hanger has four horizontally bent elements 45 arranged in pairs at or near each opposite end. The elements 45 of each pair are bent in opposite directions, one slidably engaging the upper surface of one of the tracks 22 and the other slidably engaging the upper surface of the other track of the pair. The area of engagement is made relatively small to reduce friction to a minimum and yet retain strength. Each hanger has two cross-pins 46 positioned below the tracks 22 as shown in Figs. 8, 9 and 10 to prevent upward movement of the hangers or rocking movements thereof. The spacing between the upper surface of the pin 46 and the lower surface of the tracks 22 is such as to allow for free sliding motion, with no binding.

The lower margin of each hanger has attached thereto, as by brazing, a cylindrical bead 50 which is adapted to be slidably received by a slotted marginal tubular element 51 provided at the top of each panel section 52, see also Fig. 11. In Fig. 8 only one of the panel sections 52 has been shown attached to a hanger. In Figs. 1 and 9 curtains or panels are shown as made of a plurality of detachably interlocking sections.

Now referring to Figs. 10 and 11. Each section 52 is provided with the cylindrical tubular member 51 along its top margin. The top of this tubular element has a slot extending its full length as indicated at 53. The bottom of each panel section 52 is provided with a cylindrical bead 55. At each opposite vertical edge each section is provided also with a terminal cylindrical bead 56. The beads 50, 55 and 56 are of substantially the same outer diameter which is substantially the same as the inner diameter of the slotted tubular bead 51. Thus, any tubular slotted member 51 can be attached to a bead 50 or to a bead 55 and any sealing member, now to be described, can be attached to any bead or cylinder 50, 55, or 56. This is a feature of the invention.

The body portion of the section may be less

than one-eighth of an inch thick, and the body portion of each hanger is about the same thickness. The sections are reenforced by elements which also act in an ornamental capacity. These elements are indicated at 58. Any suitable ornamentation may be provided on the front of the section, but the back is preferably smooth.

A very important feature of my invention is the means for sealing against dust, or flying 10 particles, or liquid leakage. This means comprises an element usable either as a sealing element, or as a sealing and a locking element. It can be used on a single one-piece panel or curtain, or on a plural-piece panel or curtain. Where 15 the curtain is made up of a plurality of detachable sections, the element is used both for locking the sections against accidental disconnection and for sealing. This element is generally designated 60 and can be made of any suitable shape. It is made of resilient and flexible material such as rubber. It is so made that when forcibly moved from an initial position it will automatically again assume that position when the force ceases to act. It has a flange-like extension or 20 sealing portion 61 preferably tapered as shown, and has a locking and attaching portion generally designated 62. The locking portion has the form of a slotted cylinder, the slot of which is indicated at 63. The cylindrical structure really provides 25 what may be called two flexible tapered fingers which are designated 64 and this structure permits the device 60 to be connected with one or with a plurality of aligned beads 56, or with a bead 55 in the manner shown in Figs. 5 and 9. 30 When attached to the bottom of the curtain as in Fig. 4 it extends beyond the end of the bead 55 to abut the wall as shown. The fingers 64 allow the element 60 to be "clipped over" a bead by movement in a direction perpendicular to the 35 long dimension. The element 60 can of course 40 be attached to a bead or beads by lengthwise sliding motion.

Because of the flexibility and resiliency these 45 elements 60 can act as shown in Figs. 19 and 20 to pass one another when the pendent panels 52 are adjusted by linear movement, and it is a feature of these elements that they normally occupy an angular position. This angle may be about 30°, see Fig. 20. The tip 66 may touch a line 68 which makes an angle of about 30° with the plane of motion of the panel. It will be noted in Figs. 19 to 21 that the element 60, after being deformed during adjustment of the panels, always again assumes an initial position which assures sealing 55 contact with one of the other panels or with a wall or tub or floor, after the panels have been adjusted to their final positions. The angular position may be varied.

Thus, each sealing element 60 is resilient and 60 flexible so that it can yield when engaged by another sealing element as the curtains are slid. It is seen that after one of the extensions engages another extension as shown in Fig. 19, both may be flexed but each resumes its normal or initial 65 outstanding position as soon as the flexing force ceases.

Fig. 10 shows a plurality of panel sections 52 interlocked and held against accidental unlocking by means of sealing and locking elements 60. In 70 this figure large portions of each panel section are broken away, so that the figure is somewhat diagrammatic. Nevertheless, the principle of the formation of the curtain by sections and of locking of these sections and with sealing members 75 is illustrated.

An advantage of making the curtain in sections is that any section can be replaced and any number of sections can be combined to make a curtain of the proper length or width. Each curtain is independently supported and can therefore be moved independently to any desired position longitudinally. The sections of the curtain can be assembled at the factory by sliding one within the other and the sections can then be secured against accidental disconnection by a combined locking and sealing member which can be "clipped" on.

It has been stated that the sealing members assume an angular relation to the direction of movement of the sheet and therefore to the surface of greatest area of the sheet. The angle that the sealing member makes with this surface is preferably not greater than 45° but may be somewhat less than that. This angle will vary conformably to transverse spacing between the curtains, as slidably hung on the tracks.

The overall thickness of each curtain, including the slotted tubular marginal element at the top, can be three-eighths of an inch or less. Thus, the overall transverse dimension of a plurality of curtains as hung can be, allowing for slight spacing between the curtains, about an inch and a half. The spacing between two tracks may be about one-eighth of an inch. Each track may be about five-sixteenths of an inch thick. There is no limitation of principle intended by the giving of these measurements. They are given to show how compact in transverse dimension the three curtains, as hung, can be. Each curtain may be made in one piece or panel, but each is preferably constituted by superposed sections detachably connected edge-to-edge. I believe it is entirely new to make shower curtains, of stiff material, that is of nonwoven stiff material, and also new to make the curtains of detachable sections of stiff material, of different vertical heights, so that curtains of different lengths may be had.

Another feature, in addition to the use of stiff curtain or panel sections of plastic material, is that the sections can be put up in sets or can be sold separately on order and in proper dimensions to provide any desired length or width of curtain or panel. Although I have found that a section about 21 inches in horizontal length by about 12 inches in vertical dimension is a good average size, yet some sections can have a vertical dimension of 3 or 6 or 9 inches, and of course the long dimensions would be varied conformably to the number of curtains used, which in turn must conform to the horizontal dimension of the area to be protected.

Another feature of the invention is the provision of means by which a knock-down curtain assembly can be provided, and can be attached to vertical rods, which may extend from floor or ceiling or from the top of the tub to the ceiling, one at each end of the space to be protected, and near opposite walls of the space.

Referring to Figs. 17 and 18. The lower section 70 of each tube has inserted in it at the top a flanged bushing 71 provided interiorally with threads and solidly attached within the tube 70 as by press fit, to prevent turning. The upper section or tube 73 is shorter than the lower section 70 and has inserted within at its bottom portion a jack screw 74 which is solidly anchored by means of a suitable pin 75. This screw engages the threads of the bushing 71. There is an opening 76 provided in the head portion 77 of the screw and the tube 73 for the insertion of

tool by which to forcibly turn the screw and thus expand or lengthen the tubes so that the vacuum cups 80 at the opposite ends are pressed respectively against the ceiling and the tub or against the ceiling and the floor. A slip sleeve 81, conceals the screw 74, pin 75 and opening 76. This provides a very satisfactory anchor for the tubes or rods, in an upright position. After clamping the tubes the slip sleeve 81 is dropped to the position shown. All metal parts are made of non-corrosive material.

I believe it entirely new to make a bath curtain of stiff or rigid material and to provide flexible marginal sealing elements on it, and also the first to make those elements detachable. I also believe myself the first to provide any curtain or screen made of interlocking elements which are held in interlocked relation by means of marginal flexible elements which perform a sealing function when the curtain is in use. I also believe myself the first to provide a structure for hanging curtains so that they can slide, and which structure can be applied to any suitable support or to the ordinary shower curtain rod or bar, and be easily adjustable for vertical heights or horizontal spacing.

What I claim is:

1. A device of the class described comprising, a support, three panels of stiff material pendently and slidably mounted on the support to be moved to overlapped positions, each panel having upright marginal extensions of flexible and resilient material some of which are adapted to sealingly engage the face of another panel and some to engage a wall, each panel also having along its bottom margin a similar sealing extension adapted to sealingly engage a surface which is below the panels.

2. A device of the class described comprising, track means, two panels each composed of a plurality of detachable sections of stiff material and slidably suspended from said track means to be moved therealong to overlapped positions, each panel having upright marginal extensions of flexible and resilient material which interlock with and secure the sections in relative position, some of said extensions adapted to sealingly engage the face of another panel and some to engage a wall, each panel also having along the bottom margin of its bottommost section a similar extension adapted to sealingly engage a surface which is below the panels.

3. A device of the class described comprising, a panel composed of a plurality of detachable sections of stiff material, said panel having upright marginal extensions of flexible and resilient material which interlock with and secure the sections in relative position, said extensions being arranged at an angle with the faces of greatest area of the panel to sealingly engage the face of another panel, said panel also having along its bottom margin a similar extension adapted to sealingly engage a surface which is below the panels.

4. A device adapted to act as a screen against the escape of liquid droplets and splashings including, a support device adapted for attachment to another support, a plurality of curtains slidably on the support device and adapted to assume overlapping and screening relation, said curtains being of relatively stiff plastic material and each having flexible and resilient marginal extensions adapted to sealingly contact other curtains and to sealingly contact and conform to the configuration of other surfaces which

form a frame for the space from which the escape of liquid is to be prevented.

5. A curtain composed of a plurality of detachably connected sections of relatively stiff material and interfitting sealing members of flexible and resilient material mounted on and detachably connecting together opposite edges of said sections and acting as marginal locks to prevent accidental disconnection of said sections.

6. A shower bath curtain composed of a plurality of detachably connected sections of relatively stiff material and members of flexible material respectively detachably interfitting parts of the sections and acting as marginal locks to prevent accidental disconnection of said sections, each section being removably connected to the next section by relative sliding motion and the said flexible member extending in a direction substantially perpendicular to the direction of said sliding motion and itself being disconnectable by motion perpendicular to its long dimension.

7. A shower bath curtain composed of a plurality of detachably connected sections of relatively stiff material and two members of flexible material at opposite edges of said curtain and each detachably interfitting the outer edge of all sections along the respective curtain edges and acting as a finishing piece and as a marginal lock to prevent accidental disconnection of said sections, and a third member of flexible material as a terminal member of the curtain and extending in a direction substantially perpendicular to the other members, each member having a slanting extension arranged at an angle to the faces of greatest area of said sections.

8. A device of the class described comprising, track means, a plurality of panels, means supporting each panel in a different plane for separate sliding motion lengthwise of the track means, each panel having means to sealingly engage the face of an adjacent panel for all positions of the panels, and each having sealing means adapted to engage a surface which is below said panels.

9. A device of the class described comprising, a plurality of tracks adapted to be suitably supported between two upright surfaces, a plurality of panels each supported in a different plane for separate sliding motion lengthwise of the tracks, the top portion of each panel extending between two of the tracks and having two supporting means engaging each of two of the tracks to move therealong, each panel having means to sealingly engage the face of an adjacent panel for all positions of the panels, and each having sealing means adapted to engage a surface which is below the panels.

10. A device of the class described comprising, track means, a plurality of panels, means supporting each panel in a different vertical plane for separate sliding motion lengthwise of the track means, each panel having a flexible element on each upright margin extending therebeyond in direction of motion of the panels and adapted to sealingly engage the face of an adjacent panel for all positions of the panels, and a flexible element on the bottom of each panel of a length greater than the length of the bottom of the panel but less than the length of a panel plus the dimension of both upright sealing elements in direction of motion.

11. A device of the class described comprising, a plurality of tracks adapted to be suitably supported between two upright surfaces, a plurality

of panels each supported in a different plane for separate sliding motion lengthwise of the tracks, the top portion of each panel extending between two of the tracks and having two supporting means engaging each of two of the tracks to move therealong, each panel having a flexible element on each upright margin and extending therebeyond in direction of motion of the panel and adapted to sealingly engage the face of an adjacent panel for all positions of the panels, and each panel having a flexible element on its bottom of a length greater than the length of the bottom of the panel but less than the length of the panel plus the dimension of both upright sealing elements in direction of motion.

12. A device of the class described comprising, track means, a plurality of panels, means supporting each panel in a different vertical plane for separate sliding motion lengthwise of the track means, each panel having a flexible element on each upright margin extending therebeyond in direction of motion of the panels and adapted to sealingly engage the face of an adjacent panel for all positions of the panels, a flexible element on the bottom of each panel of a length greater than the length of the bottom of the panel but less than the length of a panel plus the dimension of both upright sealing elements in direction of motion, each panel being composed of a plurality of separate sections detachably interlocked so as to swing about a horizontal point of interlocking and said upright sealing elements acting as locks to prevent accidental detachment of the interlocked sections.

13. A device of the class described comprising, a bar adapted to be supported between two upright surfaces, track means and means by which it can be swung about said bar, a plurality of panels, means supporting each panel in a different vertical plane for separate sliding motion lengthwise of the track means, each panel having a flexible element on each upright margin extending therebeyond in direction of motion of the panels and adapted to sealingly engage the face of an adjacent panel for all positions of the panels, and a flexible element on the bottom of each panel of a length greater than the length of the bottom of the panel but less than the length of a panel plus the dimension of both upright sealing elements in direction of motion.

14. A device of the class described comprising, a bar adapted to be supported between two upright surfaces, plural means each swingable about the bar, track means supported by said swingable means for rotation about the bar, a plurality of panels, and means supporting each panel in a different vertical plane for separate sliding motion lengthwise of the track means.

15. A device of the class described comprising, track means, a plurality of panels, means supporting each panel in a different plane for separate sliding motions lengthwise of the track means, each panel having projecting means to sealingly engage the face of an adjacent panel for all positions of the panels and each panel having sealing means on the bottom adapted to engage a surface below said panels.

16. A device of the class described comprising, a bar adapted to be supported between two upright surfaces, plural means each swingable about the bar, track means supported by said swingable means for rotation about the bar, a plurality of panels, means supporting each panel in a different vertical plane for separate sliding motion lengthwise of the track means, each panel having

upright marginal means to sealingly engage the face of an adjacent panel for all positions of the panels, and each panel having sealing means on its bottom adapted to engage a surface which is below the panel, the said track-supporting means which is swingable about the bar facilitating swinging of said panels in a direction transverse to their direction of lengthwise motion.

17. A device of the class described comprising, a bar adapted to be supported between two upright surfaces, plural means each adjustably swingable about the bar as an axis, releasable means for securing said swingable means in any adjusted position, a support bridging and rotatable in said swingable means, and panel means pendently supported by and movable lengthwise of said rotatable support.

CHARLES G. CUNNINGHAM.
